LOOM BINDER

Verner Lindsjo, Hopedale, Mass., assignor to
Draper Corporation, Hopedale, Mass., a corpora-
tion of Maine

Application September 28, 1933, Serial No. 691,370

2 Claims. (Cl. 139—185)

The present invention relates to looms, and more particularly to the shuttle engaging binders thereof.

Heretofore it has been customary to provide the shuttle boxes of the fly-shuttle looms with a binder for frictionally engaging and checking the shuttle as it enters the box. The binder is usually made to perform another function, that is, to control the protection mechanism. To this end, the binder is usually comprised of a rigid binder body pivoted at one end to the shuttle box. When the binder is engaged by the incoming shuttle it first swings laterally of the shuttle to cooperate with the protection mechanism, and then applies friction to the shuttle for the purpose stated.

It is a considerable problem to shape the shuttle engaging face of a rigid binder body so that, after the binder swings about its pivot a distance which may vary according to the adjustment of the protection mechanism, the face will properly contact the shuttle. It has been proposed to make the shuttle contacting face of the binder yielding for the purpose of causing it to conform to the side of the shuttle and thus exert frictional contact throughout a greater area. However, such constructions have been unsatisfactory, for various reasons, with the result that the standard binder in general use has continued to be the rigid binder with a rigid, curved face which admittedly has too little contact with the shuttle.

It is, accordingly, the object of my invention to provide a loom binder which has a resilient shuttle engaging face capable of conforming to the side of the shuttle but which shall not be subject to the disadvantage of prior binders provided with a yielding face.

The preferred embodiment of my invention is illustrated on the accompanying drawing, of which:

Fig. 1 is a plan view of the left hand end of the lay and the left hand shuttle box;

Fig. 2 is a longitudinal sectional view of the binder of Fig. 1, to a larger scale; and

Fig. 3 is a sectional view taken approximately on line 3—3 of Fig. 2, but to a still larger scale.

Referring to the drawing, the lay 1 is mounted on swords 2, only one of which is shown, for reciprocation toward and from the front of the loom in the usual manner. It is noted that the front of the loom is toward the bottom of the sheet in Fig. 1. The lay may carry similar shuttle boxes at opposite ends thereof but only the left hand box is herein disclosed. This shuttle

box includes a floor 3 formed on the usual metal lay-end, a front box plate 4 and a back box plate illustrated fragmentarily at 5.

The shuttle 6 is picked out of the shuttle box by picker stick 7 and may be returned or picked back into the shuttle box by similar means, not shown, at the opposite side of the loom. A binder 3 in the shuttle box is pivoted at its outer end on a bolt 9 which serves to secure the outer end of the back box plate to the lay. A suitable binder spring 10 has one end fixed to the lay as at 11 and its other end bears against the binder to swing the same forwardly toward the path of the shuttle. When the shuttle first enters the shuttle box it swings the binder rearwardly to thereby tilt the finger 12 on protector rod 13 and prevent stopping of the loom from the usual protection mechanism (not shown).

In order that the shuttle may tilt the finger 12 quickly and positively, the portion 14 of the face of the binder, which is first engaged by the incoming shuttle, is inclined at an appreciable angle to the path of the shuttle. The remainder of the face of the binder should be substantially parallel to the rear wall of the shuttle, in order to contact the same over a substantial area. Since the pivotal movement of the binder may vary with different operating conditions a rigid face on the binder would not always have proper contact with the shuttle, and I have accordingly provided a resilient surface which is capable of conforming to the shuttle.

In the present embodiment of my invention, while the binder body is rigid, the face of the binder is recessed from a point 15, which is about the longitudinal center of the binder body, to a point 16 adjacent the hole 17 for the pivot bolt 9. The shuttle engaging member 18 is constituted by a flat, spring steel plate which may have its surface covered with leather as at 19. This member has its inner-end fixed to the binder body, as by bolts 20, 20, and extends substantially across the recess in the binder body.

The outer free end of the member 18 is normally biased toward the path of the shuttle, but movement of the member in that direction is limited by means herein constituted by a flat plate 21 which is secured to the face of the binder body as by bolts 22, 22 and overlaps the free end of the member 18. A leaf spring 23 is housed within the recess and is bowed intermediate its ends into contact with the member 18. The point of contact 24 with the member is intermediate the ends of the latter, it having been found that such construction contributes materially to the

ability of the resilient member to conform to the wall of the shuttle.

The spring 23 is a "leaf" spring in the sense that it is formed of flat stock. It need not necessarily be laminated. In the construction shown the spring is integral with a flat portion 25 which extends along the back wall of the recess to form a backing for the spring. The spring contacts its backing at its outer end 26. An adjusting screw 27 is threaded into a nut 28 embedded in the binder body. The screw may carry a lock nut 29. The end of the adjusting screw contacts the backing 25 adjacent the outer end thereof and, in an obvious manner, may be utilized to vary the effective strength of the spring 23.

The contact points 24 and 26 should be provided with a film of grease or oil, there being a relative sliding movement between the contacting parts. When the adjusting screw is properly adjusted and the contact points mentioned properly lubricated the binder proves to be very efficient in operation. At the same time, the present construction provides no weak parts which might be subject to excessive breakage, has no rubber pads to deteriorate, and is devoid of other objectionable features of prior art constructions. However, changes may be made in the construction disclosed, within the scope of the appended claims, without departing from the spirit of the invention.

I claim:

1. A shuttle box for looms, having a binder therein, said binder being comprised of a rigid

35.

binder body having the face thereof recessed throughout a substantial proportion of its length, a resilient shuttle engaging member having one end fixed to said binder body and having its other end free and extending across said recess, a plate secured to the face of said binder body and overlapping the said free end of said member for limiting movement of the latter toward the shuttle, and a leaf spring positioned within said recess, said spring being comprised of a backing bearing against said binder body and a resilient arm connected to the backing and bearing laterally against said member intermediate the ends of the latter.

2. A shuttle box for looms, having a binder therein, said binder being comprised of a rigid binder body pivoted at its outer end to the shuttle box and having the face thereof recessed from about the center of the binder body to a point adjacent the pivot point thereof, a resilient shuttle engaging member having its inner end fixed to the said face of the binder and having its outer end free, said member extending substantially across said recess, a plate at the outer end of said binder body which plate overlaps the said free end of said member for limiting movement of the latter toward the shuttle, a leaf spring housed within said recess, said spring being comprised of a backing bearing against said binder body and a resilient arm connected to the backing and bearing laterally against said member intermediate the ends of the latter.
